(57) CLAIM

The ornamental design for a housing for photoelectric control, as shown and described.

DESCRIPTION

FIG. 1 is a front perspective view of a housing for a photoelectric control embodying my invention;

FIG. 2 is a top plan view of the housing depicted in FIG. 1;

FIG. 3 is a side elevational view of the housing depicted in FIG. 1. The opposite side elevational view is a mirror image of FIG. 3;

FIG. 4 is a bottom plan view of the housing depicted in FIG. 1;

FIG. 5 is a front elevational view of the housing depicted in FIG. 1; and,

FIG. 6 is a rear elevational view of the housing depicted in FIG. 1.
